UNITED STATES PATENT OFFICE.

FRANK E. SEELEY, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

CAP FOR ELECTRICAL ATTACHMENT-PLUGS AND THE LIKE.

No. 886,468.

Specification of Letters Patent.

Patented Nov. 20, 1906.

Application filed April 23, 1906. Serial No. 313,284.

To all whom it may concern:

Be it known that I, FRANK E. SEELEY, a citizen of the United States of America, residing in Bridgeport, in the county of Fairfield, in the State of Connecticut, have invented certain new and useful Improvements in Caps for Electrical Attachment-Plugs and the Like, of which the following is a specification.

The object of my invention is to provide for the metallic caps of electrical attachment-plugs, sockets, and the like a simple form of fastening which will at the same time be secure and present a good appearance. This object I attain by the construction I will now describe.

In the accompanying drawings, Figure 1 is a side view of an attachment-plug embodying my invention. Fig. 2 is a view of the cap and insulating - disk detached from each other. Fig. 3 is an inverted plan view of the plug, Fig. 1. Fig. 4 is a view of the insulating-disk and attached cap, partly in section. Fig. 5 is a section on the line 5 5, Fig. 2, drawn to a larger scale; and Fig. 6 is a view of an electric-lamp socket provided with my invention.

My invention may be applied to many different forms of attachment-plugs or sockets, and those illustrated are shown only by way of example.

In the form of plug shown in Figs. 1 to 5 the insulating-body A of the plug carries the usual two terminals 7 and 8 of the Edison type, and a part of this body is a disk A' of porcelain and the like, provided with pockets 9 on its under face to contain nuts 10 in such way that the nuts cannot turn in the pockets. Headed screws 11, passing from the outside of the rims of the disk through radial openings in the latter, are threaded with nuts 10.

B is the metallic cap having an insulating-bushing b, through which the insulated wires pass to be connected up to the terminals on the back of the insulating - disk A'. The common way of securing this cap on the plug has been to cut in the edge of its flange 12 bayonet-slots; but this form of fastening is neither as secure nor as sightly as might be wished. I meet the difficulty by cutting in the edge of the flange straight notches 13 to pass over the stems of the screws and by punching or otherwise form on the outer face of the flange adjacent to both edges of each notch projections 14 in such position adjacent to the edge of the flange that when the cap has been fitted onto the disk A' and the screws 11 screwed up the projections 14 will be in engagement with the heads 15 of the screws, as shown in Figs. 1, 3, and 4, and hold the cap from being pulled off until the screws are turned back far enough to free their heads from said projections.

In Fig. 6 I have shown my described construction of fastening as applied to an electric-lamp socket of the type shown in the Perkins patent No. 626,937, dated June 13, 1899, as will be readily understood.

I claim as my invention—

The combination of a body part having headed screws with a metallic cap having notches to pass over the stems of the screws and adjacent projections to engage the head of the screw.

In testimony whereof I have signed my name to this specification in the presence of two subscribing witnesses.

FRANK E. SEELEY.
